UNITED STATES PATENT OFFICE.

JOHN H. SCHUSSLER, OF DENVER, COLORADO, ASSIGNOR OF ONE-FOURTH
TO FREDERICK B. STEVENSON, OF DENVER, COLORADO.

INKING-ROLL MECHANISM FOR PRINTING-PRESSES.

SPECIFICATION forming part of Letters Patent No. 769,640, dated September 6, 1904.

Application filed October 23, 1902. Serial No. 128,508. (No model.)

To all whom it may concern:

Be it known that I, JOHN H. SCHUSSLER, a citizen of the United States of America, residing at Denver, in the county of Arapahoe and State of Colorado, have invented certain new and useful Improvements in Inking-Roll Mechanism for Printing-PresSES; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in inking-roll mechanism for printing-presSES.

My special object is to prevent the endwise movement of the inking-rolls while traveling over the type-surface, since any movement of 20 this character has a tendency to smear or blur the type-face, thus preventing the best results. There is a tendency of the inking-rolls to move endwise by reason of the endwise movement of the ink-distributing roll, the 25 friction between the distributing-roll and the inking-rolls being sufficient to produce this result. In order that the inking-rolls may work free, there is considerable clearness between the shoulders at the inner extremities 30 of the journals and the frame forming the boxes or bearings for the journals; hence the tendency to endwise movement by virtue of the action of the distributing-roll. By reason of my improvement the endwise movement of the distributing-roll may continue 35 while the inking-rolls are traveling over the type-surface, whereas without my improvement provision must be made for stopping the endwise movement of the distributing-roll 40 while the inking-rolls are traveling over the type-face.

The invention consists, further, of other features whereby the distributing-roll may be readily detached from the frame in which it 45 is journaled, all of which will now be described in detail, reference being made to the accompanying drawings, in which is illustrated an embodiment thereof.

In the drawings, Figure 1 is a side eleva-

tion of a portion of a printing-press equipped 50 with my improvements. Fig. 2 is a plan view of the inking-roll mechanism, shown on an enlarged scale, the distributing - roll being partly broken away. Fig. 3 is an end elevation of the same. Fig. 4 is a view of the same 55 with the gears removed. Fig. 5 is a detail view of the distributing-roll and its connections. Fig. 6 is an end view of the frame carrying the adjustable journal-box of the distributing-roll. Fig. 7 is a top view of the 60 same. Fig. 8 is a fragmentary view of one of the inking-rolls provided with my improvements.

The same reference characters indicate the 65 same parts in all the views.

Let the numeral 5 designate the frame of the machine; 6, the ink - disk; 7, the spring-held rods connected with the rolls, and 8 the pivoted frame on which the rolls are mounted. The inking-rolls 9 are provided with trucks 10, having journals 10^a engaging frames 12, with which one rod 7 is connected on each side of the main frame part 5. The other rod 7 on each side is connected with an auxiliary inking-roll 13, which, however, need not be described 70 in detail in this application. My improvement in connection with the inking-rolls consists in providing each roll or the truck thereof at each end with an annular flange 14. These flanges engage the tracks 15 of the frame on 75 the inside and hold the rolls 9 against endwise movement while passing over the printing-surface 5^a. The distributing-roll 16 is journaled at its extremities in boxes 17, slidably mounted in cast brackets 18, which are 80 secured to the hook-frames 12 by screws 19^a. The upper part of each bracket 18 is provided with a recess 18^a, in which the box 17 is slidably mounted. The upper portion of each of these brackets on opposite sides of the recess 85 18^a is provided with grooves forming ways in which is inserted a plate 19, normally held in place by a spring 20, secured to the bracket by screws 21^a and provided with a hook 20^a, which passes through an opening in the bracket 90 95 and enters a recess 19^a, formed in one edge of the plate 19. The center of this plate is provided with a threaded opening in which is in-

serted a set-bolt 21, which engages the top of the box 17 and holds the distributing-roll 16 down upon the inking-rolls 9 with any desired tension. By loosening the set-bolt the plate 19 may be moved laterally in the direction indicated by the arrow in Fig. 7 against the action of the spring, since the bottom of the recess 19^a is curved in one direction and provided with a shoulder or offset in the opposite direction. By removing the plates 19 the distributing-roll may be removed from the apparatus for cleaning purposes or when for any reason it may be necessary or desirable to do so. The bolt 21 is provided with a lock-nut 22, which holds the said bolt in any desired position of adjustment.

Mounted on one extremity of one of the distributing-roll journals which is extended beyond the box 17 for the purpose, as shown at 16^a, is a pinion 23, having flanges 23^a extending beyond its cogged periphery and forming a circumferential groove, into which projects a cam or spiral gear 24, which meshes with the pinion. This cam-gear is mounted on a spindle 25, carried by the depending arm 18^c, formed integral with the bracket 18 on one side of the machine. The function of the cam or spiral gear 24 and the pinion 23 is to impart the endwise movement to the roll 16, whereby the ink is evenly distributed on the rolls 9. The spindle of the roll 16 is constructed and mounted to slide endwise to permit the said movement of the roll within the limits required by the action of the cam-gear. By adjusting the bolt the pressure of the distributing-roll on the inking-rolls may be regulated at will, and the flanges 14, which engage the tracks 15 on the inside, as aforesaid, prevent this action of the distributing-roll from imparting a corresponding movement to the inking-rolls, since an endwise movement of the last-named rolls is not desirable, for reasons heretofore stated.

Having thus described my invention, what I claim is—

1. The combination with the inking-rolls of a platen printing-press, a distributing-roll mounted to engage the two inking-rolls and having an endwise movement, and a track, of 50 trucks or wheels mounted on the inking-rolls and provided with vertically-disposed flanges which engage the track and prevent the endwise movement of the inking-rolls while passing over the type or printing surfaces.
2. In a platen printing-press, the combination with a suitable frame and a track, of inking-rolls provided with trucks or wheels having vertically-disposed flanges adapted to engage the track of the press on the inside and 60 prevent endwise movement.

3. In a platen printing-press, the combination with an endwise-movable distributing-roll, of inking-rolls engaged by the distributing-roll, the said inking-rolls having trucks or wheels provided with vertically-disposed flanges engaging the track of the press to prevent endwise movement of the inking-rolls.

4. The combination with the inking-rolls of a printing-press, and a frame in which said rolls are journaled, of an endwise-movable distributing-roll engaging the inking-rolls, brackets mounted on the said frame and having openings or recesses, boxes slideable in said recesses and receiving the journals of the distributing-roll, and plates slidably connected with the brackets to close said recesses.

5. The combination with the inking-rolls of a printing-press, and the frames in which said rolls are journaled, of an endwise-movable distributing-roll engaging the inking-rolls, brackets mounted on the said frames and having openings or recesses, boxes slideable in said recesses and receiving the journals of the distributing-roll, plates slidably connected with the brackets to close said recesses, and adjusting-bolts threaded in the plates and engaging the boxes for the purpose set forth.

6. The combination with the inking-rolls of a printing-press, and the frames in which said rolls are journaled, of an endwise-movable distributing-roll engaging the inking-rolls, brackets mounted on the said frames and having openings or recesses, boxes slideable in said recesses and receiving the journals of the distributing-roll, plates slidably connected with the brackets to close said recesses, adjusting-bolts threaded in the plates and engaging the boxes, and suitable means for normally holding the said plates in place for the purpose set forth.

7. The combination with the inking-rolls of a printing-press, and the frames in which said rolls are journaled, of an endwise-movable distributing-roll engaging the inking-rolls, brackets mounted on the said frames and having openings or recesses, boxes slideable in said recesses and receiving the journals of the distributing-roll, plates slidably connected with the brackets to close said recesses, adjusting-bolts threaded in the plates and engaging the boxes, and springs mounted on the brackets for holding the said plates in place against accidental displacement.

In testimony whereof I affix my signature in presence of two witnesses.

JOHN H. SCHUSSLER.
